Primary Examiner — Darcey E Gottschalk*Assistant Examiner* — Bailey M Knotts(74) *Attorney, Agent, or Firm* — WPAT, PC(57) **CLAIM**

The ornamental design for a handheld light as shown and described.

DESCRIPTION

FIG. 1 is a perspective view of a handheld light showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view showing the status of use thereof; and,

FIG. 9 is another perspective view showing the status of use thereof.

The broken lines depict portions of the handled light that form no part of the claim.
